UNITED STATES PATENT OFFICE.

OSCAR L. SMITH, OF GRAND RAPIDS, MICHIGAN.

DISPLAY DEVICE.

1,161,901.

Specification of Letters Patent. Patented Nov. 30, 1915.

Application filed January 20, 1912, Serial No. 672,384. Renewed October 25, 1915. Serial No. 57,869.

To all whom it may concern:

Be it known that I, OSCAR L. SMITH, a citizen of the United States, residing at Grand Rapids, in the county of Kent and State of Michigan, have invented an Improvement in Display Devices, of which the following description, in connection with the accompanying drawings, is a specification, like numerals on the drawings representing like parts.

The invention to be hereinafter described relates to display devices for exhibiting merchandise in stores and other places and more particularly to such devices for exhibiting garments, wherein such garments are supported by a rack which may be movable to and from a position within a show case.

That the garments may be readily accessible, and yet be properly protected, the show case is usually provided with one or more doors. Economy of floor space is an important factor in store exhibition, so that swinging doors of the usual type become objectionable. Moreover, such old type of door, in addition to blocking the passageway between cases when open, is liable to injury. In a prior application, Serial No. 664,753, filed by me December 9, 1911, there is shown, described and claimed a door construction for a show case, wherein the front or closing end of the door is connected to the case by swinging members which, in addition to their swinging function, determined the movement of the front end of the door and confined it to movement in a circular path as it is opened and closed, while the rear end of the door is supported upon guides extending into the case along the side thereof.

The aims and purposes of the present invention are to improve such door and provide among other features means whereby, as the front end of the door is swung from and to closing position, the rear end thereof will be caused to move properly into and out of the case in substantially parallel relation to the side of the case, and the door when in open position be properly housed within the case into non-interfering relation with the garment supporting rack.

The accompanying drawings show one form or embodiment of the invention, which in connection with the following description will make clear the salient features thereof, it being understood that the details

may be varied within its true scope which is definitely set forth by the claims.

In the drawings: Figure 1 is a front view of a show case provided with two doors which are of like character, some of the parts being broken away; Fig. 2 is a detail showing how the rear end of the door is supported upon the floor of the case; Fig. 3 is a sectional detail on the line 3—3, Fig. 4; and Fig. 4 is a horizontal section of the case and door showing by full lines the door in closed position and by dotted lines the characteristic movement of the door as it moves from closed to full open position.

The show case 1 may be of any approved or desired form, and as shown comprises the base 2 supporting a floor 3. The case is preferably formed of glass sides, back and top, as fully explained in said prior application. A rack 4 supported by suitable means, such, for instance, as the uprights 5, is preferably movable to and from a position within the case in order that when at the front of the case the garments sustained by the rack may be readily accessible, as by turning movement of the rack, and when within the case that the door or doors may be closed. The rack itself forms no essential part of the present invention and may be of any desired character.

In the illustrated form of the invention, two doors 6, 6 are shown, but one door may in certain instances be sufficient, and since both doors and their mountings are alike, a description of one will be sufficient. The door 6 is preferably formed of a frame work, as shown, supporting a glass panel 7, but while this is a convenient form of structure it is not essential.

Secured to the bottom or floor 3 of the case is a socket plate 8, Figs. 1 and 3, having a recess or socket portion 9 for the pintle or pivot 10 of an arm 11 which is substantially one-half the length of the door between its front and rear ends, as indicated in Fig. 4. The free end of the arm 11 is connected to the front end of the door at 12, the connection being conveniently formed by a socket plate 13, Fig. 4, secured to the front end of the door and engaged pivotally by a pin extending from the end of the arm 11. It is to be noted that the pivotal connection of the arm 11 with the floor 3 is at the front of the case and at a point substantially midway between the front and rear ends of the

door, the construction being such that as the front end of the door is swung outward from closed position as indicated in Fig. 4, the arm 11 will turn on its pivot 10 to cause the front end of the door to swing in the arc of a circle the center of which is at the front of the case midway the length of the door. As the opening movement is continued, the arm 11 supports the front end of the door and causes it to continue in its circular path, until the door is fully opened, at which time the end 12 of the arm 11 will be at the side of the case in substantially a reverse direction from that shown in Fig. 4 when the door is closed. A similar arm 14 may be employed at the top of the case and door, see Fig. 1, and such construction is desirable where the door is large or heavy. The arm 14 when used is connected to the framing at the top of the case at 15 in a manner substantially the same as that described for the connection of the arm 11 at the bottom, and the pivotal points 10 and 15 are in vertical alinement. Likewise the free end of the arm 14 will be connected to the front end of the door at 16 in a manner similar to the connection of the arm 11 to the lower part of the door at 12, and the pivotal points 12 and 16 will likewise be in vertical alinement. Secured to the top and bottom of the case are the trackways 17, 17 which extend from front to rear of the case parallel to the sides thereof. These trackways serve to guide the rear edge of the door inward parallel to the case after such inward movement has been initiated, as will presently appear, and to this end are each engaged by a guide or roller 19, one at the top and one at the bottom of the door at the rear end thereof, as indicated in Figs. 1, 2 and 4.

As hereinbefore stated, the front end of the door is supported by the arm 11 as it swings to and from closed position, and such door support at the front end may be more or less augmented by the arm 14 at the top. In order to support the rear end of the door, the latter at its rear end is provided with a swinging frame 20 pivotally connected to the lower rear end, such pivotal connection being conveniently made by the pin 21 supporting the lower guide roller 19, Fig. 2. The swinging frame 20 has an arm 22 through which passes the pin 21, and an upright flange 23 from which extend lugs or ears for supporting the roller 24 which travels in the lower trackway 17. Secured to the rear end of the door, as by screws 25, is a bearing plate 26 curved, as indicated in Fig. 4, and having the vertical face 27, Fig. 2, against which bears the flange 23 of the swinging frame 20. The lower edge portion 28 of the curved bearing plate 26 is engaged by and rests upon the arm 22 of the swinging frame, as indicated in Fig. 2, the construction being such that as the rear end

of the door moves back and forth in the case, the swinging frame 20 rides along the bearing plate and effectively sustains the weight of the rear portion of the door, as will be readily understood from Figs. 2 and 4. Thus it will be noted that while the guide rollers 19 determine the path of movement of the rear end of the door by engagement with the trackways 17, the roller 24 traveling along the lower trackway gives reliable and effective support to the rear end of the door through the swinging frame and its engagement with the bearing plate. Obviously, the curvature of the bearing plate 26 is preferably and conveniently in the arc of a circle, the center of which is the axis of swing of the swinging frame, but the essentials of the invention in this respect do not require strict adherence to this arc of curvature, as it might be varied somewhat.

Since the front end of the door is confined to movement in the arc of a circle, the center of which is at the pivot 10 of the arm 11, and since the rear end of the door is confined to movement in a substantially straight line to and from the rear and along the side of the case, difficulty is liable to be encountered in securing the desired directional movement of the rear end of the door when the front end of the door starts from and approaches the closed position. In other words, when the front end of the door is moving in that part of its circular arc remote from the side of the case, there is little or no tendency of the rear end of the door to travel in a direction to or from the rear of the case, so that in moving the front end to closed position, the rear end is liable to remain some distance back of its closed position and prevent proper closing movement; and, similarly, in starting to open the door by grasping or moving its front end outward, there is little or no tendency for the rear end to start into the case in its straight path of movement. However, since the front end moves in a circular path and the rear end moves in a straight path, there is a point between the front and rear ends of the door about which the door may be made to swing as on a pivot, but such pivot will be a shifting pivot. The present invention takes advantage of this fact in the provision of means to initiate rearward movement of the rear end of the door when the door starts from its closed position and to insure frontward movement of the rear end of the door when the front end is approaching closed position, with the result that notwithstanding the fact that the front end of the door moves in the arc of a circle and substantially through a semi-circle during its opening and closing movements, and the rear end moves in a straight or substantially straight path tangent to the circular arc, the door not only readily moves in its prescribed paths with

ease and without special attention on the part of the operator, but when in closed position its front and rear ends are accurately positioned.

5 As one means to the above ends, the plate 8 at the bottom of the case is provided with flanges 30 constituting an open guideway extending diagonally toward the front and side of the case, as indicated in Fig. 4. Co-
10 operating with this guideway is a part attached to the door, conveniently formed as a roller 31 sustained by an arm 32 secured to the inside lower frame piece of the door, Figs. 3 and 4. While the parts described
15 constitute a good practical form of this feature of the invention which is intended to initiate and finish the movement of the rear end of the door as the front end starts to open and completes its closing movements,
20 respectively, it is to be understood that the invention is not restricted thereto and that in form and relation these parts may vary from those shown and described as one embodiment of the invention. For instance,
25 the flanges 30 need not project from the plate 8, nor be formed thereon, nor need they extend above the plane of the floor, but the invention is inclusive of all such modifications as readily suggest themselves to those
30 skilled in the art.

The guideway 33 formed by the flanges 30 is preferably open at one end as shown in Fig. 4, and the roller 31 is adapted to move between the flanges as the door approaches
35 and leaves its closed position, so that during the major portion of the opening and closing movements the roller 31 may be free from the guideway, but under these conditions the front end of the door is moving in
40 that part of its circular path under the action of the arm 11, that the rear end of the door is readily forced to move in its rectilinear path without the aid of the guideway 30 and roller 31.

45 Let it be assumed that the door is closed, as indicated by full lines Fig. 4, and is desired to be opened. The operator draws the front end of the door outward and the arm 11 defines its outward movement as in
50 the arc of a circle. The rear end, that is the left, Fig. 4, cannot move to the left at such time owing to the guideway 17 and guide roller 19, so that in the absence of any means to start the rear end of the door into the
55 cabinet, the door would bind and require that its rear or left end be pushed inward in order to open the door at all, but since the guideway 33 and roller or pin 31 confine movement of the door between its ends to a
60 pivotal shifting movement, the rear end of the door is compelled to start movement in a direction generally opposite to that of the front end and toward the rear of the case as defined by the guideway 33 and roller
65 31, the parts then assuming positions as

indicated by the dotted lines *a*, Fig. 4. As opening movement of the door continues, the roller 31 and guideway 33 continue to direct the movement of the rear end of the door into the case until the movement of 70 the front end of the door, as determined by the arm 11, has reached that part of its circular path that insures that the rear end of the door shall move into the case, whereupon the guideway 33 and roller 31 become 75 disengaged, and the rear end of the door is then guided by the trackways 17. The door may then be moved successively into the dotted line *b* position and finally be completely 80 opened, at which time it will be housed within the case sufficiently to not obstruct the aisle between cases or interfere with rack movement, the arm 11, at such time, being in position as in Fig. 1. It may be noted that the length of the door is or may 85 be substantially the diameter of the circle formed by movement of the front end of the door, and that the path of movement of the rear end of the door is tangent to the circle. As the door is opened the front end 90 swings back through the arc of a circle and the rear end travels in a straight path toward the front. When the front end approaches closed position, the guideway 33 and roller 31 engage and, by their shifting 95 pivotal relation in reverse order to that described, insure that the rear end of the door shall continue to move to the front of the case and complete its closing movement as the front end of the door reaches closed 100 position. During opening movement of the door, the roller 31 travels in the path indicated by the arrow lines in Fig. 4, and on closing movement it travels in the reverse 105 direction.

From the construction described as one form of the invention, it will be clear to those skilled in the art that the guiding connection between the case and the door intermediate its ends may be variously formed to 110 insure rectilinear movement of the rear end of the door as the front end moves in that part of its circular path near its closed position where such movement has little or no tendency to move the rear end of the door 115 either into or out of the case in a straight path. It will also be noted that when this guiding device is in control, the guides 17 and their coöperating rollers 19 do not determine the path of movement of the rear end of the door, and, similarly, when the guides 17 and rollers 19 are in control, the guiding device intermediate the ends of the door do not determine the path of movement 120 of the rear end of the door. From this it will be evident that the guides 17 need not continue to the front of the case, but may commence at a point within the case determined by the position of rollers 19 when the 125 guide 33 and roller 31 become disengaged. 130

What is claimed is:

1. The combination of a case, a door for the case movable horizontally to and from closed position, means connecting the front 5 end of the door with the case to cause said front end to move in a circular path during opening and closing movement of the door, connections between the case and the rear end of the door to direct movement of the 10 rear end in a straight line, and detachable groove and pin connections between the case and door intermediate its ends constituting a movable fulcrum for the door to permit the rear end of the door to move inward 15 of the case when the front end of the door is moved from closed to open position, said groove and pin being automatically disengaged as the door is swung to open position.

2. The combination of a case having sides 20 and rear wall and an open front, a door for closing the open front, guiding devices between the rear end of the door and case, means connecting the front end of the door with the case to cause the front end of the 25 door to move in a circular path as the door is opened and closed, and disengaging positive guiding connections between the case and door intermediate the ends of the door to direct the movement of the rear end of 30 the door into the case as the front end of the door is swung outward, said connections becoming disengaged as the door is swung to open position.

3. The combination of a case, a horizontally movable door for closing said case, means for supporting the front end of the door and to cause said front end to move in a circular path as the door is opened and closed, positive guiding devices between the 35 rear end of the door and the case acting to direct the rear end in a straight line into and out of the case during a part of the opening and closing movement of the door, and guiding devices between the case and door intermediate the ends of the latter forming a movable fulcrum for the door as 40 it is opened and closed, said guiding devices becoming automatically disengaged as the door is opened and automatically engaged 45 as the door is closed.

4. A case having a horizontally movable door, connections between the front end of the door and the case for causing said front end to move in the arc of a circle during 55 opening and closing movements of the door, engaging guiding connections between the rear end of the door and the case, and means between the door and case arranged intermediate the front and rear ends of the door 60 and constituting a shifting fulcrum for the door as it is swung from closed toward open position, the parts of said fulcrum becoming automatically disengaged as the door is moved to open position to permit

the entire door to move inward at the side 65 of the case.

5. The combination of a case having a horizontally movable door, an arm pivoted to the case and connected to the front end of the door to cause the front end to move 70 in a circular path, and means between the case and door and intermediate the front and rear ends of the door for insuring movement of the rear end of the door into the case and door and intermediate the front 75 path from closed position, said means comprising two members, one secured to the case and one to the door intermediate the ends thereof, and being constructed and arranged as a shifting pivot to positively control the door during a part of its opening movement and then to become disengaged. 80

6. The combination of a case having a horizontally movable door, a swinging arm connecting the case to the front end of the 85 door to cause said front end to travel in substantially a semi-circular path from its closed to its open position at the side of the case, connections between the case and door intermediate the ends of the latter, said connections comprising a projection on one part and a flange on the other adapted to be disengaged automatically as the door is moved from closed to open position, and guiding devices between the rear end of the 90 door and case to direct the rear end of the door to the back of the case. 95

7. The combination of a case having a horizontally movable door, a swinging arm connecting the case to the front end of the 100 door to cause said front end to travel in substantially a semi-circular path from its closed to its open position at the side of the case, connections between the case and door intermediate the ends of the latter to direct 105 the rear end of the door into the case as the door is moved from closed toward open position and to be then disengaged to permit the door to move bodily toward the side of the case, guiding devices between the door 110 and case to direct the rear end of the door to the back of the case after its inward movement has been started, and means for supporting the rear end of the door. 115

8. The combination of a case having a 118 horizontally movable door, a swinging arm connecting the case to the front end of the door to cause said front end to travel in substantially a semi-circular path from its 120 closed to its open position at the side of the case, connections between the case and door intermediate the ends of the latter forming a shifting fulcrum to direct the rear end of the door into the case as the front end is moved outward, said connections comprising 125 a guideway on one and a device on the other to detachably engage said guideway, and guiding devices between the door and

case to direct the rear end of the door to the back of the case.

9. The combination of a case or cabinet, a door, movable in a horizontal plane for opening and closing the case or cabinet, guiding devices at the rear of the door and at the side of the case or cabinet for guiding and supporting the rear portion of the door, pivotally mounted arms connecting the front edge of the door with the case or cabinet, 25 a shifting pivot for the door intermediate the two ends of the door, said shifting pivot comprising an open guide and projection, one on the case or cabinet and the other on the door, adapted to be disengaged as the door is opened and to become engaged as the door is closed.

10. The combination of a case or cabinet, a door movable in a horizontal plane for opening and closing the case or cabinet,

guiding devices at the rear of the door and at the side of the case or cabinet for guiding and supporting the rear portion of the door, pivotally mounted arms connecting the front edge of the door with the case or cabinet, 25 a shifting pivot for the door intermediate the two ends of the door, said shifting pivot comprising a guide extending at an angle to the front of the cabinet and a projection on the door adapted to engage and disengage said guide as the door is closed and opened.

In testimony whereof, I have signed my name to this specification, in the presence of two subscribing witnesses.

OSCAR L. SMITH.
